UNITED STATES PATENT OFFICE

170,119

COMBINATION SCREW DRIVER AND
REAMER

William D. Hull, Chicago, Ill.

Application October 31, 1952, Serial No. 22,080

Term of patent 14 years

(Cl. D93—4)

To all whom it may concern:

Be it known that I, William D. Hull, a citizen of the United States and residing at Chicago, Cook County, and State of Illinois, have invented a new, original, and ornamental Design for a Combination Screw Driver and Reamer, of which the following is a specification, reference being had to the accompanying drawing, forming a part hereof.

Figure 1 is a perspective view of a combination screw driver and reamer, showing my new design.

Figure 2 is a sectional view along the line 2—2 of Figure 1.

I claim:

The ornamental design for a combination screw driver and reamer, substantially as shown.

WILLIAM D. HULL.
